SHIP DOOR

Francis M. Lambert, Narberth, Pa., assignor to
 Heintz Manufacturing Company, Philadelphia,
 Pa., a corporation of Pennsylvania

Application September 11, 1945, Serial No. 615,643

7 Claims. (Cl. 114—117)

1

This invention relates to doors for ships bulkhead openings and the like, and more particularly to a pair of doors disposed on opposite surfaces of a bulkhead opening, the doors being mounted for pivotal movement about vertical axes adjacent opposite edges of the opening. Doors of the general type to which the invention relates are known as clam shell doors and in accordance with the present invention mechanism is provided so that when either door is opened, the other door will automatically open to a corresponding degree. It is a general object of the invention to provide a door structure having such mechanism.

Another object of the invention resides in the provision, in such a door structure, of tension means which act to apply greatest pressure on the doors when they are in closed position, the effect of such tension means diminishing, in a direction tending to close the doors, as the doors reach their open position.

The invention has for a still further object the provision of means, in such a door structure, for holding the doors in open position. Such holding means may be released manually by one desiring to close the door, or may be released through pneumatic or hydraulic means controlled at some distance from the door, as for example, from the bridge of the ship.

These and other objects of the invention will become more apparent from the following description and claims when read in conjunction with the accompanying drawings, in which:

Fig. 1 is a front elevational view of the invention;

Fig. 2 is a top plan view;

Fig. 3 is a view taken on the line 3—3 of Fig. 7;

Fig. 4 is a view taken on the line 4—4 of Fig. 7;

Fig. 5 is a view taken on the line 5—5 of Fig. 7;

Fig. 6 is an enlarged detail view taken on the line 6—6 of Fig. 9;

Fig. 7 is a view taken on the line 7—7 of Fig. 4;

Fig. 8 is a view taken on the line 8—8 of Fig. 4;

Fig. 9 is a section taken on the line 9—9 of Fig. 7;

Fig. 10 is a perspective detail view of a rocker arm used with the invention; and

Fig. 11 is a perspective detail view of a safety arm forming a part of the mechanism.

Referring now to the drawings, the reference

numeral 10 indicates a bulkhead frame provided with strengthening ribs 11. The bulkhead frame 10 has a door opening and this frame, adjacent the edges of the door opening, is provided with outstanding edge flanges 12 and 13 (see Fig. 2). These edge flanges 12 and 13 are adapted to be engaged by a gasket carried by each of the two doors 14 and 15 respectively adjacent their edges. The door 14 is mounted for swinging movement about the axis A (Fig. 2) while the door 15 is adapted for swinging movement about the axis B.

Both doors are similarly mounted and a brief description of the mounting for the door 14 should suffice. Door 14 is provided with two hinge supports 16 and 17 to which are pivotally mounted, respectively, the hinge blades 18 and 19. The other ends of the hinge blades 18 and 19 extend through guide members 20 and 21, respectively, and are rigidly secured to a tubular shaft 22. Bracing members 23 and 24 act to reinforce the mounting of the hinge blades 18 and 19 with respect to the tubular shaft 22.

Mounted on the bulkhead frame 10 is a bracket carrying a bearing member 25 having an upwardly extending shaft 26 on which the lower end of the tubular shaft 22 is disposed for turning movement. The upper end of the tubular shaft 22 is likewise mounted for rotation about a shaft 27, Fig. 9, as will be described.

As previously mentioned, the arrangement is such that when either door is opened and swung about its pivotal axis, the other door is correspondingly opened in the opposite direction and to a corresponding degree. This complementary opening and closing movement of the two doors 14 and 15 is accomplished in the following manner. Above the door openings, the bulkhead frame 10 is provided with a rectangular opening in which is mounted a housing 28 for the operating mechanism. From an examination of Figs. 2 and 3 it will be noted that this housing 28 may be comprised of two portions which extend on opposite sides of the bulkhead frame 10, the housing 28 as a whole being disposed with its major axis at an angle to the plane of the bulkhead frame.

With reference now to Figs. 7 and 9, it will be noted that the housing at one end (the left end in Fig. 1) is provided with aligned sleeves 29 and 30 enclosing bearings 31 and 32 for the shaft 27, the lower end of which comprises a stub axle for the tubular shaft 22. The reference numeral 33 indicates washers in the sleeves 29 and 30 while packing is indicated by the reference numerals

34, 35 and 36. Intermediate the bearings 31 and 32, the shaft 27 is squared and has mounted thereon a sprocket 37, spacers 38 on each side of a cam 39, and a sprocket 40, the purpose of which elements will be hereinafter described.

The housing 28 (see Figs. 2 and 8) at its other end, also is provided with sleeves 41, 42, and bearing structure for mounting a shaft 43, the portion of the shaft intermediate the sleeves being squared and on which portion are mounted a sprocket 44, a sleeve 45, and a sprocket 46. The lower end of shaft 43 likewise terminates in a stub shaft portion for rotatably receiving the tubular shaft 47 similarly to the manner in which tubular shaft 27 is mounted as shown in Fig. 9.

Referring now to Fig. 3, the sprocket 40 and the sprocket 46 are joined by a roller chain 48 one end of which is secured as at 49 to the sprocket 40 while the other end is secured as at 50 to the sprocket 46. Reference numeral 51 indicates a take-up mechanism for taking up slack in the chain. In a similar manner (now referring to Fig. 5), the sprocket 37 is connected to the sprocket 44 by means of a roller chain 52 one end of which is connected to the sprocket 37 while the other end is connected to the sprocket 44. Reference numeral 53 indicates a slack take-up mechanism for the roller chain 52.

Referring back to Fig. 1, it will be noted that the tubular shaft 22 is provided with an arm 54 which is joined to an arm 55 rigidly mounted on the shaft 27. Similarly, but not shown, the tubular shaft 47 for the door 15 has an arm joined to an arm carried by the shaft 43. Consequently, and because of the chain connected sprockets described, it should now be apparent that, for example, when the door 14 is opened, it will effect turning movement of the tubular shaft 22 and its arm 54 and such turning movement will be transmitted by the arm 55 to the shaft 27, which shaft will rotate in a clockwise direction. Because of the connecting roller chains, the shaft 43 for the other door 15 will also rotate in a clockwise direction.

In clam shell doors of this general type, it has sometimes been the practice to apply spring means to cause the doors to close automatically. Such spring means, however, have usually been devised so that their effect increases as the doors are opened and decreases as the doors reach their closed position. Such arrangements have several disadvantages in that they do not apply spring force at the point where it is most needed. The present invention, in contra-distinction to such known spring means, is so devised that the effect of the spring tension in a direction toward closing the doors will be greatest at the beginning of the opening of the doors, decreasing in intensity as the door reaches its open position. Moreover, because of a special lever arrangement the spring tension, as the door is being closed, is so applied as to exert its greatest effect in turning the doors about their pivotal axes. Such spring force consequently renders it easier to effect closing movement.

The mechanism for accomplishing the results referred to above will now be described. With reference now to Figs. 4, 6, 7, 8, and 9, it will be recalled that the shaft 27 has a cam 39 and spacers 38 disposed thereon between the sprockets 37 and 40. In Fig. 6 the shape of the cam member 39 is perhaps most clear. The cam surface is generally circular in contour and is provided with two notches 56 and 57. Pivottally mounted

in the housing 28 on the pivot pin 58 is a rocker arm 59, a perspective view of which is illustrated in Fig. 10. The rocker arm is provided with a roller 60 intermediate its ends, which roller engages the cam surface. Secured to the lower end of the rocker arm 59 by means of a pin 61 is a turn buckle assembly 62, the eye bolt 63 of which passes around the pin 61. The other end of the turn buckle assembly 62 is joined to a helical tension spring 64, the other end of which is connected to a roller chain 65 (see Fig. 4). The roller chain 65 at its other end is attached to a lever 66 which is tangential to the shaft 43, and may be integral with shaft 43 or with sleeve 45 (see Figs. 4 and 8).

Fig. 11 is a perspective view of a safety pin 67 provided with a roller 68. From Figs. 4, 6, and 9, it will be seen that the safety arm 67 is pivotally mounted as at 69 with respect to the housing 20 and is provided with an extension 70 which moves with the safety arm. The end of the extension 70, in turn, is pivotally connected to a bolt 71 which comprises the actuated member of a sylphon bellows assembly 72.

25 The mechanism just described operates in the following manner. When either of the doors 14 or 15 is opened by means of its respective handle 73, 74, the other door will open correspondingly because of the roller chain connections described and illustrated in Figs. 3 and 5. Turning movement of the shafts 27 and 43 will likewise cause rotation of the cam member 39 on the shaft 27, and of the sleeve 45 and lever bar 66 on the shaft 43. As the doors begin 30 their opening movement the helical spring 64 will stretch and the effect of the spring toward maintaining the doors closed is at its greatest because of the position of the lever bar 66 and the leverage on shaft 43. This will be apparent 35 from an examination of Fig. 4. However, as the doors approach their open position, the lever 66 has moved clockwise so that the axis of the spring 64 is substantially in line with the shaft 43. Consequently, there will be little tendency 40 for the spring to exert force to turn the shaft 43 in a counterclockwise direction.

Turning now to Fig. 6, it will be noted that when the door is opened substantially to fully 45 open position, the roller 68 on the safety arm 67 will engage the notch 57 in the cam 39, since the cam has rotated clockwise so that the notch 57 is adjacent the roller 68. The engagement of the roller 68 in the notch 57 thus holds the doors 50 in their open position. They may, however, be released by a pull on the doors toward closing 55 position or they may be released through the bellows Sylphon assembly which may be controlled by pneumatic or hydraulic pressure from 60 a point remote from the door, as for example, from the bridge of the ship. Actuation of the Sylphon will result in moving the bolt 71 upwardly thus moving the safety arm to the full line position shown in Fig. 6 thus removing roller 65 68 from notch 67. As soon as the shaft 43 has moved counterclockwise a short distance, the position of the lever 66 changes and consequently also the axis of the spring and the spring will thus exert its greatest force to close the doors.

70 It is of course apparent that where no latching in open position is desired, the pressure medium may be cut off from the Sylphon bellows so that the safety arm 67 and its roller 68 will not bear against the cam. Where this is the 75 case the doors consequently will only remain

open as long as they are held in open position manually.

The roller 60 of the roller arm 59 partially engages the notch 56 when the door is in closed position and thus helps to maintain the door in closed position.

With this arrangement it will be apparent that the spring force is applied with its greatest intensity, where it is most valuable, namely, to effect closing movement of the doors. Moreover, this arrangement makes for easier operation since the force required to open the door decreases as the door reaches its fully opened position at which point the spring exerts but little force on the shaft 43 to turn it toward closing position.

Having now described the invention, it will be apparent that changes in the structure and arrangement of the parts may be effected without departing from the scope thereof. The invention, therefore, should not be limited except as limited in the following claims.

I claim:

1. A door structure comprising a frame having a door opening therein, a pair of doors disposed on opposite surfaces of said frame, means for mounting the doors for pivotal movement about vertical axes which are disposed adjacent opposite side edges of the door opening, said frame having an upper opening therein above the door opening, a housing secured to the frame and enclosing said upper opening, a pair of shafts mounted in said housing and connected respectively to turn with said doors about their pivotal axes, means connecting said shafts for moving both doors between open and closed positions when one of said doors is moved, a lever mounted to turn with one of said shafts and extending laterally therefrom when the doors are in closed position, a helical spring connected at one end adjacent the other of said shafts, and flexible means forming a continuation of said spring and connecting the other end of said spring to the free end of said lever.

2. A door structure comprising a frame having a door opening therein, a pair of doors disposed on opposite surfaces of said frame, means for mounting the doors for pivotal movement about vertical axes which are disposed adjacent opposite side edges of the door opening, said frame having an upper opening therein above the door opening, a housing secured to the frame and enclosing said upper opening, a pair of shafts mounted in said housing and connected respectively to turn with said doors about their pivotal axes, means connecting said shafts for moving both doors between open and closed position when one of said doors is moved, a lever mounted to turn with one of said shafts and extending laterally therefrom when the doors are in closed position, a cam mounted to rotate with the other shaft, a rocker arm pivoted to said housing and having a roller engaging the cam surface, a helical spring connecting said rocker arm and the free end of said lever and urging said roller against the cam surface.

3. A door structure comprising a frame having a door opening therein, a pair of doors disposed on opposite surfaces of said frames, means for mounting the doors for pivotal movement about vertical axes which are disposed adjacent opposite side edges of the door opening, said frame having an upper opening therein above the door opening, a housing secured to the frame and enclosing said upper opening, a pair of shafts mounted in said housing and connected respec-

tively to turn with said doors about their pivotal axes, means connecting said shafts for moving both doors between open and closed position when one of said doors is moved, a lever mounted to turn with one of said shafts and extending laterally therefrom when the doors are in closed position, a cam mounted to rotate with the other shaft, a rocker arm pivoted to said housing and having a roller engaging the cam surface, a helical spring connecting said rocker arm and the free end of said lever and urging said roller against the cam surface, a safety arm pivotally mounted within said housing and having a roller engaging the cam surface, said cam having a notch adapted to be engaged by the roller on the safety arm when the doors are in open position to releasably retain them in open position.

4. A door structure comprising a frame having a door opening therein, a pair of doors disposed on opposite surfaces of said frame, means for mounting the doors for pivotal movement about vertical axes which are disposed adjacent opposite side edges of the door opening, said frame having an upper opening therein above the door opening, a housing secured to the frame and enclosing said upper opening, a pair of shafts mounted in said housing and connected respectively to turn with said doors about their pivotal axes, means connecting said shafts for moving both doors between open and closed position when one of said doors is moved, a lever mounted to turn with one of said shafts and extending laterally therefrom when the doors are in closed position, a cam mounted to rotate with the other shaft, a rocker arm pivoted to said housing and having a roller engaging the cam surface, a helical spring connecting said rocker arm and the free end of said lever and urging said roller against the cam surface, a safety arm pivotally mounted with said housing and having a roller engaging the cam surface, said cam having a notch adapted to be engaged by the roller on the safety arm when the doors are in open position to releasably retain them in open position, and means for moving said safety arm to release its roller from said notch when it is desired to close the doors automatically.

5. A pair of doors for closing a single opening, each of said doors being of a size to completely close the opening, means for mounting the doors for pivoting movement about two separate axes, which are located adjacent opposite side edges of the door opening and are located one on each side of the plane of said opening, rotatable shafts aligned with each of said axes, sprockets mounted on said shafts for turning movement with said doors about each axis, chain means connecting said sprockets to transmit pivoting movement of either door to the other, a helical spring held at one end adjacent one of said sprockets, a lever movable with the shaft carrying the other sprocket, and flexible means connecting said helical spring with said lever at a point spaced from the axis of rotation of the shaft with which said lever moves, said lever being mounted so as to move said point of attachment away from said spring when said doors are opened and simultaneously to shorten the effective lever arm to diminish the effect of said spring in urging said doors toward closed position, said flexible means being effective, despite movement of said lever to a dead center or over center position, to transmit the force of said spring to said lever arm in such manner as to

cause said lever to be urged in a door closing direction at all times with at least part of the force of said spring, regardless of the dead center or over center location of said lever.

6. The combination set forth in claim 5, there being two sprockets spaced apart on each of said shafts in an axial direction, each sprocket lying in the same plane as a sprocket on the other shaft, said lever and the spring being located between said two planes.

7. A pair of doors for closing a single opening in a frame, each of said doors being of a size as to completely close the opening, means for mounting the doors to said frame for pivoting movement, the pivotal axis of one of the doors being disposed adjacent one side edge of the door opening in said frame and spaced from the plane of the opening in a first direction, the pivotal axis of the other door being disposed adjacent the opposite side edge of the door opening in said frame and spaced from the plane of the opening in a second direction opposite to said first direction, elements coaxial with the axes of each of said doors and mounted to turn therewith, lever means fixedly mounted to one of said elements and extending laterally therefrom, movement transmitting means connecting the elements whereby pivoting movement of

either of the doors will effect a corresponding pivoting of the other door, spring means connected at one end to said frame and at the other end to said lever means and operable in all positions of the doors for urging one of said elements to move in a direction tending to close said doors, and mechanism including said lever means for disposing said spring means in a position in which it exerts a substantially decreased effect on such closing movement when the doors are in their open position.
